COUNTER ACTUATING MECHANISM

Benno Cohn, Brooklyn, N. Y., assignor to Ferdinand Gutmann & Co., New York, N. Y., a corporation of New York

Application May 3, 1933, Serial No. 669,117

14 Claims. (Cl. 235—98)

The invention relates to a counter actuating mechanism, and more particularly to such a mechanism by which the number of articles delivered to a container is accurately determined.

Heretofore, when filling containers with bottle closures and similar articles, it has been the practice notwithstanding that the price of such articles is based on gross or thousand lots, to fill a container therewith and then arrive at an approximation of the number of articles in the container by weighing the container and its contents. Such closure caps or similar articles have very little weight so that the number packed in different containers may vary widely due to the slight differences in the weights of different closures, or wide differences in the weights of different containers.

The selling price of bottle closures and like articles, in the packaging of which my invention is particularly designed for use, is low and such articles are used in very large numbers. It is therefore desirable that the number of caps delivered be known to correspond with the number for which the purchaser is charged.

In the packaging of such caps after they are completely assembled and inspected, the common practice has been to deliver them directly to the container in which they are to be shipped to the consumer. The delivery of the caps, while rapid, is not in a continuous stream due at times to the functioning of the assembling machine, and at other times to a varying interval required for inspection.

The individual caps have insufficient weight to physically actuate a counting mechanism and the hand counting of such caps involves a prohibitive cost.

The machine of the invention embodies therein a progressively operative mechanical counter, there being associated with this counter a continuously operating source of power, the operative effect of which upon the counter is determined by mechanisms controlled by succeeding caps in their progress from the inspection table to the container in which they are to be packed. Because of the light weight of the individual caps, and the irregularity in the movement of succeeding caps toward the container, I provide an electric circuit controlling mechanism actuated by the cap itself, and a mechanism controlling the movement of the caps while approaching said circuit controlling mechanism, for the purpose of affording a time interval sufficient to ensure the actuation of the counter mechanism. In this manner, the movement of caps in such a rapid succession as to preclude the operation of

the counter mechanism, with the passage of each cap in relation to the electric circuit controlling mechanism, is prevented.

The mechanisms applying power to the counter and controlling the application of such power, are so constructed and arranged that in the event of irregular spacing of caps, due to the clogging of a delivery chute or other conveyor device or of the failure to keep the chute or other device properly filled, the actuation of the counter will be interrupted until there has been a resumption of a proper feeding movement of the caps.

Such mechanisms are also so constructed and arranged that if the delivery chute or other device should be clogged while a cap is operative in its relation to the electric control mechanism, no power will be applied to the counter. In fact, the construction of the counter actuating mechanism and its controls is such that while each cap, as it approaches the point of its delivery to a container, causes the operative connection of a continuously operating source of power to a counter actuating mechanism, the counter is not fully actuated to register the delivery of this cap until it has moved out of its operative relation to the electrical control mechanism actuated thereby and is about to pass into the container. This ensures absolute accuracy of the count of closures delivered to the container, since any failure to deliver caps, or any irregularity in the timing of the delivery of said caps will result in the interruption of the application of power to the counter although immediately upon the resumption of the proper delivery and the proper timing of such caps there will be an automatic resumption of the application of power to the counter.

To secure the above results, accuracy in the timing of the mechanism controlling the movement of the caps in relation to the electrical control mechanism and of the electrically controlled clutch mechanism connecting the source of power with the counter actuating mechanism is required, although the construction and arrangement of parts of the latter mechanism is such as to avoid the necessity for any great nicety in the timing arrangement. In fact, the timing of the movement of the closure in relation to the electrical control mechanism actuated by the cap is determined by an electrical make and break mechanism included in the counter actuating mechanism, so that the delivery of caps in relation to the switch mechanism controlled thereby is determined by the position of the parts of the counter actuating mechanism during each cycle of operations of said mechanisms.

If there be a regular and continuous movement of the caps toward the container, the source of power will be uninterruptedly connected with the counter actuating mechanism, but whenever there is an interruption in the feeding movement of caps, the power applied to the counter will be instantly interrupted and the counter actuating mechanism will remain idle until there has been a resumption of a feeding movement of the caps. Likewise, in the event of the stoppage of the movement of caps toward the container, whether one of these caps be in the operative relation with the electrical control device or not, there will be an interruption of the application of power to the counter until this condition is remedied.

The mechanism of the invention is so constructed that the feeding of the caps or other articles and the application of power to the counter actuating mechanism will be automatically interrupted upon the delivery of a predetermined number of caps or other articles to the container, this result being accomplished by employing a well known form of counter mechanism including therein an electrical control device which becomes operative when a predetermined number has been registered upon the counter, to stop the feeding movement of the caps in relation to the electrical mechanism actuated thereby to cause the application of power to the counter. This stoppage of the machine permits removal of a filled container and the substitution of an empty container therefor, manually operative means being provided whereby the counter controlled stop mechanism may be made inoperative so as to permit a resumption of the normal functioning of the machine in delivering and counting caps or other articles.

The invention consists primarily in a counter actuating mechanism embodying therein an article delivery mechanism, a counter of the type having a stop mechanism operative following a predetermined number of actuations of the counter, a counter actuating mechanism, a continuously operating source of power, co-operating clutch members, one of which is operative upon said counter actuating mechanism, and the other of which is actuated by said source of power, electrically actuated means whereby said clutch members may be made operative or inoperative, an electrical source, circuit means from said source including said electrically actuated means, and an electrical device controlling said circuit, said device being associated with, and actuated by and in accordance with the position of an article in, said delivery mechanism, whereby the operative relation of an article to said control device will cause the operation of said electrically actuated means to set said clutch members to transmit power to said counter actuating mechanism, and the passing of an article out of such operative relation will cause the operation of said electrically actuated means to disengage such clutch members upon the completion of a cycle; and in such other novel features of construction and combination of parts as are hereinafter set forth and described and more particularly pointed out in the claims here- to appended.

Referring to the drawings,

Fig. 1 is a diagrammatic showing of a packaging machine embodying the invention;

Fig. 2 is a detailed view in elevation of the operative mechanisms of the machine;

Fig. 3 is a section on the line 3—3 of Fig. 2;

Fig. 4 is a section on the line 4—4 of Fig. 2; and

Fig. 5 is a view of the modified form of the controlling device for the circuit including the clutch actuating means.

Like numerals refer to like parts throughout the several views.

In the embodiment of the invention illustrated in the drawings, the construction and arrangement of parts is such as to adapt the machine to the packaging of bottle caps. In the drawings, I have indicated at 10 a counter mechanism having progressively actuated counter wheels and circuit making connections by which an electrical circuit is closed when the wheels have reached a predetermined setting. This counter mechanism is old and well known in the art and may have a wide range of structural variation. United States Letters Patent No. 20,100,1409 discloses a counter of the general type referred to. The mechanism may be such as to afford a visual register of the number of caps being delivered or not, as desired. The automatic electrical stop mechanism actuated by the counter elements in accordance with the predetermined setting of the counter is the main characteristic of this mechanism desirable in the machine of the invention.

This counter has power applied thereto to cause the progressive actuation of the various digit wheels, or other members, through an actuating mechanism comprising a shaft 11 carrying a crank 12 connected with the operating crank 13 of the counter by the link 14. Said shaft 11 has idly mounted thereon, a gear wheel 15 enmeshed with a gear wheel 16 carried by the shaft of an electric motor 17 which affords a continuously operating source of power while the packaging machine is in operation. Power is transmitted from the motor 17 through the gear train 15 and 16 to the shaft 11 by means of a clutch mechanism comprising a member 18 in the form of a ratchet wheel carried by and rotatable with the gear 15 and co-operating pawl 19 carried by an arm 20 secured to the shaft 11. The pawl 18 is pivoted to the arm 20 and is acted upon by a spring 21 having a constant tendency to engage said pawl with said ratchet wheel.

Since continuous engagement of the pawl 19 with the ratchet 18 would ensure the actuation of the counter with each revolution of the shaft 11, it is necessary to provide means whereby said pawl is permitted to operatively engage said ratchet wheel only when a closure cap or other article has been properly fed so as to be delivered to a container, and is made inoperative to engage said ratchet wheel at all other times while the machine is operating. Such means comprises two cams 22 and 23 positioned adjacent the periphery of the ratchet wheel 18 in substantially diametrically opposite relation to each other. These cams 22 and 23 co-operate with an anti-friction roller 24 carried by the pawl 19, and are supported by a rock arm 25 pivoted at 26.

Said rock arm is electrically actuated by means of an electro-magnet 27 having an armature 28 connected with the rock arm 25 by a link 29.

The cams 22 and 23 are so spaced in relation to each other and to the ratchet wheel 18 that when the electro-magnet 27 is energized the lower cam 22 will be positioned out of the path of movement of the roller 24 and the upper cam 23 will be positioned in the path of movement of said roller and when said electro-mag-

net is de-energized, the cam 23 will be positioned out of, and the cam 22 will be positioned in, the path of said roller. The function of the lower cam 22 is to prevent the setting of the clutch mechanism 18 and 19 in case of irregularity in the spacing of caps during their feeding movement toward the container or of the absence of such caps in the feeding mechanism; while the function of the cam 23 is to interrupt the operation of the counter actuating mechanism in the event of the clogging of the delivery mechanism or the stoppage of the feeding movement of a cap therein.

In the operation of the machine, it is essential that the arm 25 receive one full direct and return reciprocation as each cap is delivered to the container and that its movements be accurately timed in relation to the movement of the caps in a manner to be more fully referred to hereinafter.

The circuit for energizing the electro-magnet 27 is derived from a source 30 shown as an ordinary electric battery, said circuit including therein an electrical device associated with the article delivery mechanism and actuated by and in accordance with the position of an article during its movement in said delivery mechanism toward the container.

Referring more particularly to Figs. 1 to 4 of the drawings, the delivery mechanism comprises an ordinary chute 31 along which the caps or other articles are adapted to move by gravity. It is obvious that other means for assuring movement of the caps may be employed although a delivery chute has been found very effective in actual use of the machine.

Associated with the chute 31 is a fixed contact 32 and a movable contact 33 exposed interiorly of the chute through an opening in the bottom thereof. The movable contact 33 is sufficiently flexible that the weight of a cap will engage it with the fixed contact 32. One terminal of the winding of the electro-magnet 27 is connected with one terminal of the source 30 by a line 34 and the other terminal of the source is connected by a line 36 with the movable contact 33. The fixed contact 32 is electrically connected with the other terminal of the winding of the electro-magnet by the line 35.

It will be noted that when the contact 33 is disengaged from the fixed contact 32, the circuit to the magnet 27 is interrupted and the cam 22 will be in its lowermost position and when the weight of a cap or other article engages the movable contact 33 with the contact 32, the magnet 27 will be energized and the cam 22 will be in its elevated position, it being returned to its lowermost position immediately that a cap moves out of engaging relation with the contact 33.

A spring 37 acts upon the arm 25 to ensure a desired rapid downward movement of said arm and of the cams 22 and 23 following the de-energizing of the magnet 27.

Pivotedly mounted adjacent the delivery chute 31 is an escapement member 38 having two fingers 39 and 40 projecting into the chute in engaging relation with caps or other articles passing along same. The finger 40 when in its elevated position permits a cap or other article to move into engagement with the movable contact 33, the other finger 39 maintaining the cap in such engaging relation with the electrical control device for a sufficient interval to ensure at least a one-half revolution of the shaft 11. During this interval the escapement member 38 will

be so rocked as to disengage the finger 39 from the cap or other article, the finger 40 in the meanwhile being interposed in the path of succeeding caps or articles in the chute so as to prevent their movement toward the electrical control device until the complete revolution of the shaft is assured.

The escapement member 38 is actuated by means of an electro-magnet 41, the armature 42 of which is connected by a link 43 pivotally connected therewith and with one end of the rocking escapement member 38. Acting upon the escapement member 38, through the link 43, or in any other desired manner, is a spring 44.

As heretofore pointed out, the movement of the caps or other articles in relation to the electrical device controlling the circuit to the magnet 27 must be timed in relation to the operative moment of the counter actuating mechanism. A slight dwell of a cap in engaging relation with said device is required to permit movement of the roller 24 to a position where it can be no longer engaged by the lower cam 22 before the de-energizing of the magnet 27 resulting from movement of the cap, can occur; and the succeeding cap must be restrained from movement into engaging relation with the electric control device until after the roller 24 has passed the upper cam 23, since the energizing of the magnet 27 prior to this time would result in the automatic release of the clutch mechanism and the interruption of the actuation of the counter.

To secure a proper timing in the actuation of the escapement member, I include the winding of the magnet 41 in a circuit from the source 30, or 35 any other desired source, which circuit also includes therein a fixed contact 45 and a movable contact 46, the latter being actuated by means of a cam 47 carried by a cam disk 48 preferably formed of insulating material secured to and rotatable with the shaft 11. The rise of this cam is so positioned in relation to the roller 24 of the pawl 19 that it operatively engages the movable contact member 46 at an interval following the movement of said roller out of engageable relation with the lower cam 22, and said cam 47 is of a length to maintain a closed circuit by the contacts 45 and 46 until after the roller 24 has passed out of its operative relation to the upper cam 23. It is merely necessary that the setting 50 of the rise of the cam 47 shall be such as to close the circuit to the winding of the magnet 41 after the shaft 11 has been turned sufficiently to avoid disengagement of the pawl 19 from the ratchet wheel 18 by the cam 22, and that the 55 magnet 41 shall be de-energized at a time to preclude possibility of the succeeding cap in the delivery mechanism reaching its operative relation to the electrical device controlling the circuit to the magnet 27 before the roller 24 has passed the 60 cam 23.

By this is meant that there is a certain time interval between the de-energizing of the magnet 41 and the movement of a cap from its position, determined by the engagement of the finger 40 65 therewith, to its engaging relation with the member 33 of the electrical control device. This interval, however, is very short, since the machine of the invention is capable of developing a speed amounting to two hundred or more cycles per 70 minute.

One terminal of the winding of the magnet 41 is connected by a lead 49 with the source 30, and the other terminal of said winding is connected by a lead 50 with the fixed contact member 45, 75

the movable contact member 46 being connected by a lead 51 with the opposite pole of the source 30.

It will be noted that when the magnet 41 is energized, feeding of the caps through the chute or other article delivering mechanism 31 is prevented. This enables me to utilize the escapement mechanism to automatically stop the delivery of caps or other articles by the machine 10 when a predetermined number of such caps, as determined by the mechanisms of the counter 10, has been delivered to a container.

To accomplish this result, I connect the electrical mechanism of the counter by a lead 52 with the source 30, and also connect this mechanism by a lead 53 and the lead 50 with the winding of the magnet 41 the circuit being completed through the lead 49 between the magnet 41 and the source. With this wiring, the electrical mechanism of the counter 10 acts as a circuit control device maintaining the circuit, including same and the magnet 41, open until the delivery of a predetermined number of caps has been registered upon the counter mechanism 10, whereupon, irrespective of the position of all other mechanisms in the machine, the delivery of caps will be stopped in a manner to be hereinafter referred to. Preferably, I provide in the length of the line 53 a manually operative switch 54 which is normally closed but which may be manually opened to re-start the operation of the machine following the removal of a full container, shown at 55 in Fig. 1, and the substitution of an empty container therefor.

35 Referring to Fig. 5 of the drawings, I have illustrated an electrical control device which may be used in lieu of the cooperating contacts 32 and 33. In this embodiment of the invention, I provide opposite sides of the chute 31 with aligned openings, shown at 56 and 57. Adjacent one of these openings, I provide a source of light 58, and adjacent the other opening, a photo-electric cell 59 responsive to the light rays from said source. The cell 59 actuates a relay mechanism 60 controlling a circuit including therein the winding of the magnet 27. One of the leads 61 of the relay is connected with a source, such as 30, and the other lead 62 thereof is connected with one terminal of the winding of said electro-magnet 27, the circuit being completed by the lead 34 from said magnet to the source.

In Fig. 4 of the drawings I have shown two succeeding caps 63—64, the foremost 63 of which is in operative relation to the mechanism controlling the circuit to the magnet 27, it being held in this position by the finger 39 of the escapement mechanism. Ordinarily such closures have a metal shell, and when the machine is used for packaging same, the movable contact member 33 is provided with a portion 65 of insulating material to prevent short circuiting of the source through the metal shell of the container and the delivery chute.

65 The operation of the herein described machine is substantially as follows:—

The operation of the machine will be described in relation to its use in connection with the packaging of bottle caps, it being understood that in its use in connection with other articles, the delivery mechanism will require modification to adapt it to use with such particular articles.

In the drawings, the relation of parts is such as will occur immediately following the operative engagement of a cap 63 with the movable contact member 33. With this condition, the

magnet 27 is energized and the arm 25 is in its uppermost position as a result of the movement of the armature 28 and the link 29. The cam 47 is out of engaging relation with the movable contact member 46 so that the circuit for energizing the magnet 41 is open. The lower cam 22 is in its elevated position so that the spring 21 is permitted to engage the pawl 19 with a tooth of the ratchet wheel 18. The finger 39 of the escapement mechanism is in the path of movement of the cap 63 in operative relation with the electrical device controlling the circuit to the magnet 27, thus maintaining the cap 63 in the operative relation to the control device.

As heretofore stated, the motor 17 is in continuous operation while the machine is in use and imparts continuous rotary movement to the ratchet wheel 18 so that immediately upon the engagement of the pawl 19 with one of the teeth of said ratchet wheel, the arm 20 and with it the shaft 11, receives rotary movement from the motor 17 and the gear train connecting same with the ratchet wheel 18.

Immediately following movement of the pawl 19 a number of degrees in excess of the degrees in arc of the cam 22, the rise of the cam 47 by contact with the movable member 46 engages it with the fixed contact member 45, thus closing the circuit to the magnet 41. The energizing of this magnet, through the armature 42 and link 43, rocks the escapement member 38 so as to move the finger 39 out of the path of the foremost cap 63 at the same time moving the finger 40 between said cap 63 and the succeeding cap 64 thus permitting the escape of the foremost cap 63 but preventing movement of the succeeding cap. In fact, the finger 40 by engagement with the cap 63 may be utilized to accelerate the discharge of this cap.

Immediately following this escapement movement and the movement of the foremost cap 63 out of engagement with the electrical control device for the circuit including the magnet 27, this magnet is de-energized and the spring 37 draws the armature 28 and the arm 25 downwardly so that when the pawl 19 approaches the upper center of the ratchet wheel 18, the cam 23 will be in its lower position so as to permit continued movement of the arm 20 and shaft 11 as a result of continued engagement of said pawl with the continuously moving ratchet wheel.

The length of the cam 47 is such that the magnet 41 will be continuously energized until after the roller 24 has passed the upper cam 23, whereupon the fall of cam 47 will permit the separation of the contact 46 from the contact 45, thus interrupting the circuit including the winding of the magnet 41 and permitting the armature to be moved by the spring 44 in a manner to rock the escapement member 38 so as to move the finger 40 out of the path of the cap 64, affording clearance for the descent of this cap by gravity into engaging relation with the electrical device controlling the circuit including the winding of the magnet 27. This will occur during the final stage of the rotation of the counter actuating mechanism, which has been referred to.

If it should occur that at this instant there is no cap in the chute in a position to move into the operative relation to said control device, the magnet 27 will not be energized and the cam 22 will remain in its low position, so that as the roller 24 reaches this cam it will be moved out of engagement with the ratchet wheel 18 and thus permit the continued free rotation of this ratchet wheel although movement of the shaft 11 will immedi- 75

ately stop. By using a ratchet wheel, notwithstanding such a temporary stoppage of the counter actuating mechanism, immediately that a cap reaches the operative relation the coupling between the continuously rotating motor and the counter actuating mechanism will be set. In this manner a hit-and-miss effect is secured, avoiding a slowing down of the machine to an extent beyond that which is unavoidable as a result of variation in the movement of the caps in the delivery mechanism. If there should be a considerable space between succeeding caps in the delivery mechanism, this would merely result in a delay in energizing the magnet 27, so that the counter will not be actuated during this interval.

If for any reason the cap 63, following the actuation of the escapement mechanism by the energizing of the magnet 41, should remain in operative relation to the electrical control device, the circuit to the magnet 27 will not be interrupted so that the cam 23 will be held in its elevated position where it will be engaged by the roller 24 and cause disengagement of the pawl 19 from the ratchet wheel 18, thus releasing the clutch mechanism connecting the source of power with the shaft 11 and interrupting the actuation of the counter after that cap 63 has been registered thereon. During this continued energizing of the magnet 27, the cam 47 will be in its operative relation to the contact 46 so as to continue to energize the magnet 41.

Upon the removal of the cap 63 from its engagement with the electrical control device, the magnet 27 will immediately be de-energized, thus permitting the spring 21 to engage the pawl 19 with the ratchet wheel so as to cause the resumption of the operation of the machine. This will be followed by the interruption of the circuit including the magnet 41.

Adverting to the form of the invention shown in Fig. 5, the mode of operation is the same as that heretofore described, with the exception that the energizing of the magnet 27 results from the actuation of the relay mechanism 60 as a result of the interposition of a cap between the light source 58 and the photoelectric cell 59, the energizing of said magnet resulting from the passage of a cap from the path of the rays emanating from said source of light.

It is obvious that whatever the form of electrical control device associated with the article delivery mechanism, the operation of the machine will be the same.

While the machine is in operation the manually operative switch mechanism 54 is closed. The circuit in which this switch is included, however, is open until the counter 10 has been actuated a number of times corresponding with the quantity of caps it is desired to pack in a container. When the registered number of caps reaches this predetermined amount, the position of the control mechanism in the counter will close the circuit including the counter, the switch 54 and the winding of the magnet 41, energizing this magnet and so positioning the finger 40 of the escapement mechanism as to interrupt the feed of the caps in the article delivery mechanism. When this occurs, the magnet 41 will be continuously energized, so that the opening of the circuit controlled by the contacts 45 and 46 will have no effect upon the escapement mechanism.

The interruption of the feeding of the caps permits the operator to remove the filled container and substitute an empty container therefor.

To re-start the machine it is merely necessary for the operator to open the circuit including the counter 10, switch mechanism 54 and winding of the magnet 41 momentarily, since with the next actuation of the counter this circuit will be broken at the counter itself. The interruption of the circuit to permit the spring 44 to rock the escapement mechanism will permit the resumption of the feeding of the caps along the chute 31.

In a machine embodying the invention, the motor 17 at all times affords adequate power to operate the counter, thus permitting, when desired, the use of a low potential source for controlling the application of the motor power to the counter actuating mechanism.

The caps or other articles will be accurately registered, irrespective of any irregularity in the timing of their movements while in the article delivery mechanism, and any failure of this mechanism will result in the stoppage of the counter actuating mechanism.

The number of teeth upon the ratchet wheel 18 is immaterial except insofar as the development of the desired speed in the actuation of the machine is concerned.

It is not my intention to limit the invention to the precise details of construction shown in the drawings, it being apparent that such are subject to wide variation to adapt the machine for use with different articles.

Having described the invention, what I claim as new and desire to have protected by Letters Patent, is:—

1. A machine of the class described embodying therein an article delivery mechanism, a counter of the type having a stop mechanism operative following a predetermined number of actuations of the counter, a counter actuating mechanism, a continuously operating source of power, co-operating clutch members, one of which is operative upon said counter actuating mechanism, and the other of which is actuated by said source of power, electrically actuated means whereby said clutch members may be made operative or inoperative, an electrical source, circuit means from said source including said electrically actuated means, and an electrical device controlling said circuit, said device being associated with, and actuated by and in accordance with the position of an article in, said delivery mechanism, whereby the operative relation of an article to said control device will cause the operation of said electrically actuated means to set said clutch members to transmit power to said counter actuating mechanism, and the passing of an article out of such operative relation will cause the operation of said electrically actuated means to disengage such clutch members upon the completion of a cycle.

2. A machine of the class described embodying therein an article delivery mechanism, a counter of the type having a stop mechanism operative following a predetermined number of actuations of the counter, a counter actuating mechanism, a continuously operating source of power, co-operating clutch members, one of which is operative upon said counter actuating mechanism, and the other of which is actuated by said source of power, electrically actuated means whereby said clutch members may be made operative or inoperative, an electrical source, circuit means from said source including said electrically actuated means, an electrical device controlling said circuit, said device being associated with, and actuated by and in accordance with the

- the position of an article in, said delivery mechanism, whereby the operative relation of an article to said control device will cause the operation of said electrically actuated means to set said clutch members to transmit power to said counter actuating mechanism, and the passing of an article out of such operative relation will cause the operation of said electrically actuated means to disengage such clutch members upon the completion of a cycle, and means operative upon said clutch mechanism, whereby in the event of the failure of an article to pass out of operative relation to said electrical control device, said clutch mechanism will be released.
3. A machine of the class described embodying therein an article delivery mechanism, a counter of the type having a stop mechanism operative following a predetermined number of actuations of the counter, a counter actuating mechanism, a continuously operating source of power, a ratchet wheel connected with said source of power, a pawl operative upon said counter actuating mechanism, means normally preventing engagement of said pawl with said ratchet wheel, electrically actuated means, connections between same and said first named means, an electrical source, circuit means from said source including said electrically actuated means, and an electrical device controlling said circuit, said device being associated with, and actuated by and in accordance with the position of an article in said delivery mechanism, whereby when an article is in operative relation to said control device, engagement of said pawl with said ratchet wheel is permitted, and when an article is not in such operative relation, said pawl will be disengaged from said ratchet wheel.
4. A machine of the class described embodying therein an article delivery mechanism, a counter of the type having a stop mechanism operative following a predetermined number of actuations of the counter, a counter actuating mechanism, a continuously operating source of power, a ratchet wheel connected with said source of power, a pawl operative upon said counter actuating mechanism, diametrically opposite cams adapted respectively to prevent or permit engagement of said pawl with said ratchet wheel, electrically actuated means, connections between same and said cams, an electrical source, circuit means from said source including said electrically actuated means, and an electrical device controlling said circuit, said device being associated with, and actuated by and in accordance with the position of an article in, said delivery mechanism, whereby when an article is in operative relation to said control device, one of said cams will be positioned to permit engagement of said pawl with said ratchet wheel when said pawl is in operative relation thereto, and the other of said cams will be positioned to disengage said pawl from said ratchet wheel when said pawl is in operative relation to said other cam, and the position of these cams will be reversed when an article is not in such operative relation.
5. A machine of the class described embodying therein an article delivery mechanism, a counter of the type having a stop mechanism operative following a predetermined number of actuations of the counter, a counter actuating mechanism, a continuously operating source of power, co-operating clutch members, one of which is operative upon said counter actuating mechanism, and the other of which is actuated by said source of power, electrically actuated
- means whereby said clutch members may be made operative or inoperative, an electrical source, intermittently operative means controlling the movement of articles in said delivery mechanism adjacent said electrically actuated means, electrically actuated means operative upon said intermittently operative means, separate circuit means from said source including respectively said electrically actuated means, a switch mechanism actuated by said counter actuating mechanism controlling the circuit to the electrically actuated means operative upon said intermittently operative means, whereby the delivery of articles is controlled by said counter actuating mechanism, and an electrical device controlling the circuit to said first named electrically actuated means, said device being associated with, and actuated by and in accordance with the position of an article in, said delivery mechanism, whereby the operative relation of an article to said control device will cause the operation of said electrically actuated means to set said clutch members to transmit power to said counter actuating mechanism, and the passing of an article out of such operative relation will cause the operation of said electrically actuated means to disengage such clutch members upon the completion of a cycle.
6. A machine of the class described embodying therein an article delivery mechanism, a counter of the type having a stop mechanism operative following a predetermined number of actuations of the counter, a counter actuating mechanism, a continuously operating source of power, co-operating clutch members, one of which is operative upon said counter actuating mechanism, and the other of which is actuated by said source of power, electrically actuated means whereby said clutch members may be made operative or inoperative, an electrical source, an escapement member having fingers controlling the movement of articles in said delivery mechanism, an electro-magnet having an armature, connections between said armature and said escapement member, separate circuit means from said source including respectively said electrically actuated means and said magnet, a switch mechanism actuated by said counter actuating mechanism controlling the circuit to said electro-magnet, whereby the delivery of articles is controlled by said counter-actuating mechanism, and an electrical device controlling the circuit to said electrically actuated means, said device being associated with, and actuated by and in accordance with the position of an article in, said delivery mechanism, whereby the operative relation of an article to said control device will cause the operation of said electrically actuated means to set said clutch members to transmit power to said counter actuating mechanism, and the passing of an article out of such operative relation will cause the operation of said electrically actuated means to disengage such clutch members upon the completion of a cycle.
7. A machine of the class described embodying therein an article delivery mechanism, a counter of the type having a stop mechanism operative following a predetermined number of actuations of the counter, a counter actuating mechanism, a continuously operating source of power, a ratchet wheel connected with said source of power, a pawl operative upon said counter actuating mechanism, means normally preventing engagement of said pawl with said ratchet wheel, electrically actuated means, connections between same and said first named means, an electrical source, an escape-

- ment member having fingers controlling the movement of articles in said delivery mechanism, an electro-magnet having an armature, connections between said armature and said escapement member, separate circuit means from said source including respectively said electrically actuated means and said magnet, a switch mechanism included in the circuit to said magnet, a cam carried by and movable with said counter actuating mechanism and co-operating with said switch mechanism, said cam being so positioned in relation to said pawl as to control the circuit to said electro-magnet following the engagement of said pawl with said ratchet wheel and until said counter has been actuated, whereby the delivery of articles is controlled by said counter actuating mechanism, 10 and a fixed electrical contact, and a movable electrical contact co-operating therewith and projecting through the opening in said chute in engageable relation with articles therein, whereby when an article engages said movable contact, engagement 15 of said pawl with said ratchet wheel is permitted, and when an article is not engaged therewith, such engagement is prevented.
10. A machine of the class embodying therein an article delivery mechanism, a counter of the type having a stop mechanism operative following a predetermined number of actuations of the counter, a counter actuating mechanism, a continuously operating source of power, a ratchet wheel connected with said source of power, a pawl operative upon said counter actuating mechanism, a rock arm adjacent said ratchet wheel supporting diametrically opposite cams adapted respectively to prevent or permit engagement of said pawl with said ratchet wheel, an electro-magnet, connections between said magnet and said arm, an electrical source, circuit means from said source including said electro-magnet, and an electrical device controlling said circuit, said device being associated with, and actuated by and in accordance with the position of an article in, said delivery mechanism, whereby when an article is in operative relation to said control device, one of said cams will be positioned to permit engagement of said pawl with said ratchet wheel, and the other of said cams will be positioned to disengage said pawl from said ratchet wheel before the completion of a cycle, if an article has not passed from the operative relation to said control device, and said first named cam will be positioned to disengage said clutch members upon the completion of a cycle, if an article is not in operative relation to said control device.
9. A machine of the class described embodying therein a delivery chute having an opening through the wall thereof, a counter of the type having a stop mechanism operative following a predetermined number of actuations of the counter, a counter actuating mechanism, a continuously operating source of power, a ratchet wheel connected with said source of power, a pawl operative upon said counter actuating mechanism, means normally preventing engagement of said pawl with said ratchet wheel, electrically actuated means, connections between same and said first named means, an electrical source, an escapement members having fingers controlling the movement of articles in said delivery mechanism, an electro-magnet having an armature, connections between said armature and said escapement member, separate circuit means from said source including
- respectively said electrically actuated means and said magnet, a switch mechanism included in the circuit to said magnet, a cam carried by and movable with said counter actuating mechanism, said cam being so positioned in relation to said pawl as to control the circuit to said electro-magnet following the engagement of said pawl with said ratchet wheel and until said counter has been actuated, whereby the delivery of articles is controlled by said counter actuating mechanism, 10 a fixed electrical contact, and a movable electrical contact co-operating therewith and projecting through the opening in said chute in engageable relation with articles therein, whereby when an article engages said movable contact, engagement 15 of said pawl with said ratchet wheel is permitted, and when an article is not engaged therewith, such engagement is prevented.
10. A machine of the class embodying therein an article delivery mechanism, a counter of the type having a stop mechanism operative following a predetermined number of actuations of the counter, a rotatable shaft, connections between said shaft and said counter, a continuously operating source of power, a ratchet wheel driven from said source of power and idly mounted upon said shaft, an arm carried by and rotatable with said shaft, a pawl thereon co-operating with said ratchet wheel, diametrically opposite cams adapted respectively to prevent or permit engagement of said pawl with said ratchet wheel, an electro-magnet having an armature, connections between said armature and said cams, a spring opposed to said magnet, an electrical source, circuit means from said source including the winding of said magnet, and an electrical device controlling said circuit, said device being associated with, and actuated by and in accordance with the position of an article in, said delivery mechanism, whereby when an article is in operative 40 relation to said control device, one of said cams will be positioned to permit engagement of said pawl with said ratchet wheel, and the other of said cams will be positioned to disengage said pawl from said ratchet wheel before the completion of a cycle, if an article has not passed from the operative relation to said control device, and said first named cam will be positioned to disengage said clutch members upon the completion of a cycle, if an article is not in operative 50 relation to said control device.
11. A machine of the class described embodying therein an article delivery mechanism, a counter of the type having a stop mechanism operative following a predetermined number of actuations of the counter, a counter actuating mechanism, a continuously operating source of power, co-operating clutch members, one of which is operative upon said counter actuating mechanism, and the other of which is actuated by said source of power, electrically actuated means whereby said clutch members may be made operative or inoperative, an electrical source, circuit means from said source including said electrically actuated means, an electrical device controlling said circuit, said device being associated with, and actuated by and in accordance with the position of an article in, said delivery mechanism, whereby the operative relation of an article to said control device will cause the operation of said electrically actuated means to set said clutch members to transmit power to said counter actuating mechanism, and the passing of an article out of such operative relation will cause the operation of said electrically actuated means 70
- 75

to disengage such clutch members upon the completion of a cycle, means whereby when said counter has been actuated a predetermined number of times the movement of articles into the operative relation to said electrical device will be prevented, and manually operative means making said last named means inoperative.

12. A machine of the class described embodying therein an article delivery mechanism, a counter of the type having circuit controlling means operative following a predetermined number of actuations of the counter, a counter actuating mechanism, a continuously operating source of power, co-operating clutch members, one of which is operative upon said counter actuating mechanism, and the other of which is actuated by said source of power, electrically actuated means whereby said clutch members may be made operative or inoperative, an electrical source, an escapement member having fingers controlling the movement of articles in said delivery mechanism, an electro-magnet having an armature, connections between said armature and said escapement member, separate circuit means from said source including respectively said electrically actuated means, the circuit controlling means of said counter and said magnet, a switch mechanism actuated by said counter actuating mechanism controlling the circuit to said electro-magnet, whereby the delivery of articles is controlled by said counter actuating mechanism, an electrical device controlling the circuit to said electrically actuated means, said device being associated with, and actuated by and in accordance with the position of an article in, said delivery mechanism, whereby the operative relation of an article to said control device will cause the operation of said electrically actuated means to set said clutch members to transmit power to said counter actuating mechanism, and the passing of an article out of such operative relation will cause the operation of said electrically actuated means to disengage such clutch members upon the completion of a cycle, and a manually operative electrical switch in the circuit including said magnet and the circuit controlling means of the counter.

13. A machine of the class described embodying therein a delivery chute having an opening through the wall thereof, a counter of the type having a stop mechanism operative following a predetermined number of actuations of the counter, a rotatable shaft, connections between said shaft and said counter, a continuously operating source of power, a ratchet wheel driven from said source of power and idly mounted upon said shaft, an arm carried by and rotatable with said shaft, a pawl thereon co-operating with said ratchet wheel, diametrically opposite cams adapted respectively to prevent or permit engagement of said pawl with said ratchet wheel, an electro-

magnet having an armature, connections between said armature and said cams, a spring opposed to said magnet, an escapement member having fingers controlling the movement of articles in said delivery mechanism, an electro-magnet having an armature, connections between said armature and said escapement member, an electrical source, circuit means from said source including the windings of said magnets respectively, a switch mechanism included in the circuit to the magnet actuating said escapement member, a cam carried by and movable with said counter actuating mechanism, said cam being so positioned in relation to said pawl as to control the circuit including said switch mechanism following the engagement of said pawl with said ratchet wheel and until said counter has been actuated, whereby the delivery of articles is controlled by said counter actuating mechanism, a fixed electrical contact and a movable electrical contact co-operating therewith and projecting through the opening in said chute in engageable relation with articles therein, said last named contacts controlling the circuit to the cam actuating electro-magnet whereby when an article engages said movable contact, said electro-magnet is energized to actuate said cam to permit engagement of said pawl with said ratchet wheel, and when an article is not engaged therewith, said electro-magnet is de-energized to move said cam in the path of movement of said pawl to disengage same therefrom upon the completion of a cycle.

14. A machine of the class described embodying therein a delivery chute having openings in the opposite sides thereof, a counter of the type having a stop mechanism operative following a predetermined number of actuations of the counter, a counter actuating mechanism, a continuously operating source of power, co-operating clutch members, one of which is operative upon said counter actuating mechanism, and the other of which is actuated by said source of power, electrically actuated means whereby said clutch members may be made operative or inoperative, an electrical source, circuit means from said source including said electrically actuated means, a source of light adjacent one of the openings for said chute, a photo-electric cell adjacent the opposite opening in said chute, and a relay controlled by said photo-electric cell and controlling the circuit including said electrically actuated means, whereby when an article is positioned between said light source and said photo-electric cell, said electrically actuated means will be operated to set said clutch mechanism and when an article passes out of such operative relation, said electrically actuated mechanism will be operated to release said clutch mechanism.
